(57) **CLAIM**

The ornamental design for fittings assembly for temporary and tight joining of ends of tubular members, as shown and described.

DESCRIPTION

FIG. 1 is a perspective view of the fitting assembly for temporary and tight joining of ends of tubular members according to a first embodiment;

FIG. 2 is a right side elevation view of a lower portion of the invention shown separately for ease of illustration, the left side being a mirror image;

FIG. 3 is a front elevation view thereof;

FIG. 4 is a top plan view thereof;

FIG. 5 is a bottom plan view thereof;

FIG. 6 is a right side elevation view of an upper portion of the invention shown separately for ease of illustration;

FIG. 7 is a left side elevation view thereof;

FIG. 8 is a front elevation view thereof;

FIG. 9 is a rear elevation view thereof;

FIG. 10 is a bottom plan view thereof;

FIG. 11 is a top plan view thereof;

FIG. 12 is a perspective view of an upper portion of the invention according to a second embodiment shown separately for ease of illustration;

FIG. 13 is a left side elevation view thereof;

FIG. 14 is a right side elevation view thereof;

FIG. 15 is a rear elevation view thereof;

FIG. 16 is a front elevation view thereof;

FIG. 17 is a bottom plan view thereof; and,

FIG. 18 is a top plan view thereof.

The broken line showing is included for the purpose of illustrating portions of the article and forms no part of the claimed design.
